United States Patent Office.

ELIJAH K. BIGELOW, OF LITCHFIELD, MICHIGAN, ASSIGNOR TO HIMSELF AND PETER COMSTOCK, OF SAME PLACE.

Letters Patent No. 102,752, dated May 10, 1870.

IMPROVEMENT IN PRUNING AND HEDGE-SHEARS.

The Schedule referred to in these Letters Patent and making part of the same

To whom it may concern:

Be it known that I, ELISHA K. BIGELOW, of Litchfield, in the county of Hillsdale and State of Michigan, have invented a new and useful Improvement in Pruning and Hedge-Shears; and I do declare that the following is a true and accurate description thereof, reference being had to the accompanying drawings and to the letters of reference marked thereon, and being a part of this specification.

In the drawing, the implement is represented closed, and its position when open is shown in dotted lines.

The nature of this invention relates to an improved construction of shears for pruning and trimming purposes, so that a drawing cut may be had by the cutting-blade being provided with a slot and set-screw; and

The invention consists in the arrangement of a spring in connection with pulleys, the handles and the cutting-blade, for the purpose of operating the shears; also, in the arrangement of its several parts.

In the accompanying drawings—

A represents a handle, preferably of wood, to which is secured the standard B, the upper part of which should be of steel, and curved to form a resisting blade, C, to the action of the cutting-blade D, which should be made substantially of the form shown in the drawings and pivoted to the standard at b.

A curved slot, a, describing a segment of a circle, whose axis is at b, is cut through the cutting-blade, and a set-screw, d, passes through this slot into the standard B. It will be noticed that the cutting-blade is curved into the form of a hook upon its lower edge, for the purpose of hooking on to and assisting to bring within reach of the operator any desired limb.

A small pulley or friction-wheel, E is pivoted to the standard B, for the purposes hereinafter mentioned.

To the handle A is also pivoted a wheel or pulley, F, to which is secured a handle, G.

A stud-spring, H, is secured to the end of the cutting-blade, as shown at h, and thence passing over the small pulley E and partially around the pulley or wheel F, is secured to its periphery at k, the whole arrangement forming a very powerful implement for the purpose.

It will be readily seen that by this device it makes no difference whether the limb to be cut off is high or low, as the apparatus for actuating the cutting-blade prevents the necessity of a great extension of the arms required, where shears of the ordinary construction, and provided with long handles, are used to actuate the cutting-blade at a distance from the operator.

What I claim as my invention, and desire to secure by Letters Patent, is—

1. The spring H, in connection with the pulleys E and F, the handles A G and the cutting-blade d, constructed and arranged as described, and for the purpose set forth.

2. The pruning-shears described, consisting of the handles A G, the standard B, provided with the curved resisting blade C, the cutting-blade D pivoted to the standard at b, operated with the slot a, set-screw d, and the spring H, all constructed and arranged as described and for the purposes set forth.

ELIJAH K. BIGELOW.
